CLAIM

The ornamental design for a telephone stand, as shown and described.

DESCRIPTION

FIG. 1 is a top, front and right side perspective view of a telephone stand showing our new design;

FIG. 2 is a top plan view thereof;

FIG. 3 is a left side elevation thereof;

FIG. 4 is a front elevation thereof;

FIG. 5 is a rear elevation thereof; and,

FIG. 6 is a bottom plan view thereof.

The broken lines are shown for purposes of illustration only and form no part of the claimed design.
